US0D1103577S

(12) **United States Design Patent** (10) **Patent No.:** **US D1,103,577 S**
(45) **Date of Patent:** **** Dec. 2, 2025**

(54) **PROTECTIVE CLOTHING**

(71) Applicant: **DECATHLON**, Villeneuve d'Ascq (FR)

(72) Inventor: **Olivia Corradini**, Villeneuve d'Ascq (FR)

(73) Assignee: **DECATHLON**, Villeneuve d'Ascq (FR)

(**) Term: **15 Years**

(21) Appl. No.: **29/917,163**

(22) Filed: **Nov. 17, 2023**

(30) **Foreign Application Priority Data**

May 22, 2023 (EM) 015022196-0001

(51) **LOC (15) Cl.** **02-02**

(52) **U.S. Cl.** **D2/731**
USPC .....

(58) **Field of Classification Search**

USPC D2/731, 717, 840

CPC A41D 13/0518

See application file for complete search history.
